KEYED HEAD BRAKE BEAM

Frank W. Lewis, Chicago, Ill., assignor to Chicago Railway Equipment Company, Chicago, Ill., a corporation of Illinois

Filed Mar. 16, 1955, Ser. No. 494,680

4 Claims. (Cl. 188—228.6)

The invention relates to railway truss type brake beams of the "Hunton" type in which the compression and tension members converge towards each other from the middle of the beam towards the ends of the beam, substantial end portions of the members being parallel and in contact with each other and mounting the brake heads.

The general objects of the invention are to effectively and simply secure the end portions of the compression and tension members to each other, to facilitate the application and removal of the brake head to and from the beam when replacement is required, and to adapt the beam and head for mounting of an interchangeable head on either end of the beam, thus avoiding the necessity of making left and right patterns for the head.

In the accompanying drawings illustrating the invention,

Figure 1 is a top view of a beam of the general type referred to and embodying one form of the invention. The right hand end of the beam is sectioned upon the line 1—1 of Figure 2 and also indicates the adjacent portion of a wheel to which the beam will be applied.

Figure 2 is a vertical section taken on the line 2—2 of Figure 3 and drawn to an enlarged scale.

Figure 3 is a horizontal section taken on the line 3—3 of Figure 2.

Figure 4 is a detail section of parts shown in Figure 2 illustrating the assembly of the parts.

Figure 5 is a section corresponding to Figure 2, but illustrating another form of the invention.

Figure 6 is a horizontal section taken on the line 6—6 of Figure 5.

Figure 7 is a horizontal section taken on the line 7—7 of Figure 5.

In the form of the invention shown in Figures 1—4, the compression member 1 is of channel section with its web upright and its flanges horizontal. Tension member 2 is of rectangular bar section with its end portions 3 of increased thickness and depth and substantially fitting between the flanges of the compression member and contacting with the inner face of the compression member web. The compression and tension members are spaced apart at the middle of the beam by a strut 10 and the tension member is inclined toward the compression member from the strut to each end of the beam. The end portions of the strut and beam are parallel and in contact with each other. Each terminal of the tension member projects lengthwise of the beam beyond the terminal of the compression member and is provided with a head 4 forming shoulders 5 and 6 facing towards the middle of the beam. Shoulder 5 is seated against the terminal of the web of compression member 1.

A strap-like retainer 11 is bent around the end portions of the compression and tension members transversely of the beam from the position shown in full lines (Figure 4) to the position shown in broken lines in which the ends 11a of the retainer are in abutting relation. Preferably the retainer is bent into its final position while

2

hot and, in shrinking, fits more tightly against the compression and tension members and holds them more tightly to each other. The middle portion of the retainer is offset at 11b to provide recesses 11c receiving the edge portions of the channel compression member flanges.

A brake head 15 includes a body portion with a transverse passageway 15a disposed to receive the end portions of the compression and tension members and the surrounding retainer 11. The forward wall of the passageway has an offset portion 16 disposed to seat against the offset portion 11b of the retainer. The rear wall of the passageway is spaced from the rear face of the compression member web and the head is apertured at 17 to receive a spring key 18. The middle portion 18a of the key is bulged forwardly and bears against the end portions of retainer 11. The end portions of the key bear against the upper and lower portions of the inner face of the back wall of the brake head passageway.

The offset portion 11b of the retainer is apertured at 19 and receives an annular rib 20 projecting from the front wall of the brake head passageway. Preferably an indentation 24 in the compression member web cooperates with shoulder 5 in positioning retainer 11 lengthwise of the beam.

With this assembly, the retainer is held against movement towards the end of the beam by the engagement therewith of shoulders 5 and 6 on the end of the tension member. The brake head is held against similar movement by the co-action of aperture 19 and rib 20. These parts are held engaged, except during assembly and disassembly, by spring key 18, which is retained against movement lengthwise of the beam by the groove 21 provided therefor in the back wall of the head passageway. To replace the head, it is only necessary to remove key 18, move the head forwardly of the beam far enough to disalign elements 19 and 20 and then slide the head off the end of the beam. The new head is replaced by reverse movements. The assembly of the compression and tension members is not affected.

Preferably the front wall of the head passageway is extended at 22 to bear against the inclined portion of tension member 2 immediately adjacent to its end portion 3, thus providing additional bearing between the head and the tension member and reinforcing the tension member at the angle of its bend. This head extension 22 projects at both sides of the head laterally of the head beyond the plane of the shoe mounting elements 23 so that the head is symmetrical about its longitudinal axis and may be applied to either end of the beam.

In the form of the invention shown in Figures 5, 6, and 7 the compression member 31 and the tension member 32 are the same as shown in Figures 1—4. There is no strap-like retaining member surrounding the tension and compression members in addition to the head 35. In lieu of the strap-like retaining member, the compression and tension members are secured together independently of the head by rivets 36 extending transversely of the beam through the end portions of the tension member and the compression member web.

The head has a through passageway for the end of the main members of the beam and is provided with parts 37, 38 extending outwardly beyond the planes of the shoe mounting elements 39 at both sides of the beam. Element 37 is seated against the inclined portion of tension member 32. Element 38 is offset rearwardly of the shoe mounting face of the brake head and its outer edge is engaged by the inwardly facing shoulder 40 on the end of the tension member. Spring key 41 draws the head rearwardly so that elements 37, 38 remain in engagement with the opposing elements of the tension member.

When the head is to be replaced, key 41 is withdrawn,

the head moved forwardly to disalign elements 38 and 40, and the head removed lengthwise of the beam. There is no interference with rivets 36 which permanently maintain the assembly of the compression and tension members.

In both forms of the invention, the head is readily replaced. The head is held against movement from the beam but has a loose fit over the beam which permits the head to rock slightly on the beam from a perpendicular and thereby cushion blows by the wheel flanges F (Figure 1) against the side of the brake shoes S as the wheels play lengthwise of the beam. This will reduce wear on the brake beam parts.

The details of the construction may be varied other than as described without departing from the spirit of the invention and the exclusive use of those modifications coming within the scope of the claims is contemplated.

What is claimed is:

1. In a railway truss type brake beam having a main compression member and a main tension member, both extending lengthwise of the beam, and spaced apart near the middle of the beam, the tension member being inclined toward the compression member from the middle of the beam toward each end of the beam, the end portions of said members at each end of the beam extending parallel and having opposing faces in contact, an elongated strap bent tightly around the top, bottom, front and rear faces of said end portions transversely of the length of the beam and retaining them together, the terminal of the tension member extending beyond the terminal of the compression member outboard of the beam and having front and rear shoulders facing toward the middle of the beam and engaging the outermost end face of the compression member and the outermost edge of the retaining strap, whereby the compression and tension members and the strap are secured against disassembly.

2. A railway truss type brake beam according to claim

1 provided with a brake head at each end of the beam having a transverse passageway receiving the end portions of the tension and compression members and receiving the retainer strap and mounted on the latter, there being opposing elements on an inner face of the brake head passageway and the front face of the retainer strap and facing lengthwise of the beam and engaging each other, upon movement of the head transversely of the length of the beam, and thereby holding the head against movement lengthwise of the beam, and a key extending through the brake head and engaging the rear face of the retaining strap to hold said elements against relative movement transversely of the length of the beam.

3. A railway truss type brake beam according to claim 1 in which the retaining strap has a shrunk fit about the end portions of the compression and tension members.

4. A railway truss type brake beam according to claim 2 in which the forward face of the passageway in the brake head bears against the forward face of the retaining strap and the inner side of the brake head bears against the forward inclined face of the tension member.
